VERTICAL FILING CABINET WITH FIXED OR MOBILE COMPARTMENTS FOR STANDING OR HANGING UP THE FOLDERS THEREIN

Otto Alfred Becker, Robert Koch Str. 59,

Saarbrücken, Germany

Original application Dec. 28, 1960, Ser. No. 78,927, now Patent No. 3,146,046, dated Aug. 25, 1964. Divided and this application Jan. 23, 1964, Ser. No. 341,832
7 Claims. (Cl. 312—234.4)

This application is a division of my copending application Serial No. 78,927, filed December 28, 1960 and which issued on August 25, 1964 as U.S. Patent No. 3,146,046.

The invention relates to a filing cabinet or the like with fixed or movable compartments for standing or hanging up the folders therein, said cabinet being fitted with an index panel carrying index strips upon which the contents of each folder in alphabetic order are shown against the numbers or other references which appear on tabs attached sequentially in staggered arrangement to the folders. Since the efficiency of such a filing system depends upon the most convenient arrangement of the index panels which are intended to permit a quick and ready general survey to be made of the files contained in each compartment, the invention which will be hereinafter described relates more particularly to and arranging index panels, or the like, for indexing folders kept in cabinets.

With stacked cabinets of similar construction at least their position in relation to the angle of view at different compartment levels will differ.

For this reason it is an advantage if the index panels or the like are arranged to be movable for instance about lateral pivot pins or hinges located above, or below, or on one side of the panels in such manner that the panels can be adjusted to a position in which they will face the direction from which they are viewed and thereby present the information they contain at the angle of optimum visibility.

Consequently an index panel associated with the bottom compartment, assuming the panel extends in the form of a band across the front of the folders, will be moved into a horizontal position, whereas a panel associated with a compartment at eye level will be moved into a vertical position, and the intermediate panels into positions of increasing angularity in accordance with their consecutively lesser height from the floor. By thus arranging for the adjustability of the panels the excellent visibility of the indexes permits individual folders to be identified quickly, easily, and without the likelihood of mistake.

Alternatively, the index panels may be located horizontally above the folders, or the like, in the compartments, each panel being preferably subdivided into sections which are individually movable. This method of arranging the indexes is especially convenient in lower drawers as the angle of view will then be straight downwards when the relative drawers are pulled out. The folders may be extracted after the index panels have been moved upwards and out of the way.

On the other hand, the lateral arrangement of movable index panels in drawer cabinets will be preferred if the level of the drawers is such that they cannot be conveniently looked into from above. In such a case it is better to provide drawers without side walls and to locate the tabs, indexes, guide cards, and so forth, on the other side of the drawer as is conventionally done in so-called side extraction filing systems.

The index panel which in the latter case is likewise divided into separate sections is arranged to be moved downwards when the desired reference has been ascertained so that the required folder can be pulled out.

2

This arrangement of folders and index panels permits seven drawers with normal sized folders to be placed the one above the other in such manner that even the top drawer will still be conveniently accessible from the side for the removal and replacement of the folders. The contents of the uppermost drawer will still be within average reach. It was hitherto impossible to superpose more than four, and at most five drawers since a person had to be exceptionally tall to look down into the top drawer of five.

An arrangement of a drawer-type filing cabinet designed on the basis of the side extraction system in conjunction with appropriate index panels therefore solves the increasingly difficult problem of finding space for large filing systems.

Instead of band-shaped index panels, for instance slideable indexes of tablet shape may be provided in vertical, inclined, or horizontal positions in front of, above, or to the side of the folders, said panels being held in one or more rails in which they can be slidably moved to and fro. A vertical arrangement of index panels is more convenient in compartments located at eye level or higher. In lower compartments an obliquely inclined, and in the bottom compartment a horizontal, position will be best to conform with the angle from which the respective index is normally seen.

For the purpose of facilitating rapid identification another possibility, especially in the case of drawer-type filing cabinets, is to provide strip indexes in horizontal and vertical groups held in rails on the face of the drawers.

If it is not desirable that such an index should be immediately visible to any person who happens to enter the office, suitable hinged flaps may be secured above or below or on the side of the index panels. This has the further advantage that the inside faces of the flaps offer additional indexing space so that any desirable enlargement of the index could be readily put into effect.

It will, of course be understood that the outside faces of flaps could also be employed for enlarging the size of the index.

Simple, convenient, and economical as this solution of the filing problem appears to be, it has nevertheless never been suggested before. This is probably due to the fact that in the past the most convenient form of indexing the files was thought to be that of providing the folders themselves with identifying descriptions and arranging them in strict alphabetical order. Moreover the advantages in folder filing systems of combining an index with folders arranged by code numbers based on the decimal system do not appear to have been appreciated. Hitherto the drawer faces were merely provided with short references to their contents, such as words like "Files from A-E."

If very compendious indexes are required the backing plates or the like may be provided with guide rails for slideable index cards. Such cards may also be provided on the inside of the faces of drawers.

Other advantages and details of the invention will be disclosed in the course of the following description of embodiments shown in the accompanying drawings in which:

FIG. 1 is a partial view of a drawer-type cabinet,
FIG. 2 is a perspective view of the indexing system illustrated in FIG. 1,

FIG. 3 is a view of part of a drawer-type cabinet with vertical index panels.

FIG. 1 is a drawer-type filing cabinet 46 with drawers 47 on extendable pull-out sliding rails 48. On their edges at the side of the drawer the folders are provided with tabs 4 which are staggered in groups of tens and thus form a filing register. Inserted between each group

of ten folders is a guide plate 5 with a tab extension 6. Slidably mounted in a guide 50 in front of these lateral edges is a vertical index panel 49. The drawer is divided down the centre and both sides carry folders in similar arrangement.

This side arrangement of the filing register is an advantage in drawers situated above the eye level as these are too high to be viewed from above. The open-side arrangement permits folders to be easily identified, removed, and replaced.

Instead of an upright slidable index panel, flap-type panels 51 which can be tilted on hinges, as shown in FIG. 3, and which carry an index on one or both faces may be provided, such panels being preferably subdivided into a plurality of separate sections. Known means may be employed to erect the panels into upright position when the drawer is closed.

Drawers of this kind may also be provided with double-sided flap type index panels 52 arranged above the folders, as is likewise shown in FIG. 1. These flaps can be tilted through an angle of 180°. Such an arrangement is especially apt for the lower drawers in a cabinet, as the user can look straight down at the indexes.

FIG. 2 illustrates a flap index 52 of the described kind and the manner in which it is hinged at 54 to a centre partition 53.

In the case of very large filing systems the guide plates 5 may be provided with guide or index cards 57 held between rails 55 and provided with projecting finger tabs 56 for pulling them out (FIG. 2). The guide plates 5 may be slidably mounted in rails 53a.

As an alternative to placing them on the sides of, above, or between the folders, index panels 58 (FIG. 1) may be affixed to the front face of the drawer. This is a useful arrangement for upper drawers but not so convenient on lower drawers, because their vertical position then makes them difficult to be read.

To overcome this objection such index panels 58 may be arranged to tilt on hinges 60 or the like affixed to their upper edges so that the index can be adjusted to any position of angularity 58a (in dotted outline) (FIG. 1).

FIG. 3 illustrates an arrangement of vertical index cards 65 affixed to the face of the drawer.

Although there has been described a preferred embodiment of this novel invention, many variations and modifications will now be apparent to those skilled in the art. Therefore, this invention is to be limited not by the specific disclosure herein, but only by the appending claims.

I claim:

1. Filing apparatus comprising a cabinet having an opening in a wall thereof; a plurality of structures within said cabinet; each of said structures defining a compartment adapted to house a plurality of folders; first means mounting a first of said structures for movement relative to said cabinet and through said opening with an end of said structure moving parallel to a side of said cabinet; index means including a panel, labeling means removably mounted to said panel and containing indicia indicating respective contacts of a plurality of folders mounted in the compartment defined by said first structure; second means mounting said panel to said first structure for movement therewith as well as for movement with respect thereto; said second mounting means permitting said panel to be in a plane generally parallel to said side of said cabinet.

2. Filing apparatus as set forth in claim 1 in which said end of said first structure is open sufficiently to permit folders to be inserted and withdrawn therethrough.

3. Filing apparatus as set forth in claim 2 in which the second means extends generally parallel to said side of said cabinet and said panel is slidably displaceable with respect to said side of said first structure.

4. Filing apparatus as set forth in claim 3 in which said panel is also pivotally mounted with respect to said second means.

5. Filing apparatus as set forth in claim 4 in which said first structure also includes a front adjacent and at right angles to the end of said first structure, said panel for all positions thereof, lies in planes generally at right angles to the front of said first structure.

6. Filing apparatus as set forth in claim 1 in which the index means also indicates at least one additional panel having labeling means removably mounted thereto, all of said panels being mounted to said second means.

7. Filing apparatus as set forth in claim 6 in which each of the panels is approximately a quarter of the depth of the compartment defined by the first structure.
